UNITED STATES PATENT OFFICE

2,370,684

COIN CONTROL APPARATUS

Charles F. Pease, Long Beach, Calif.

Application November 16, 1942, Serial No. 465,775

13 Claims. (Cl. 194—61)

My invention relates to improvements in a coin control of that type which is particularly although not exclusively adapted for use with dispensing units, such as are described in my co-pending applications: Serial Number 364,621, filed November 7, 1940; Serial Number 370,272, filed December 16, 1940, and further applications about to be filed, the inventions set forth in said applications being adapted for dispensing individual articles and packages of various kinds and shapes.

The primary object of this invention is the production of an improved coin control by which any one of a number of dispensing units of similar or different types can be operated to dispense any article chosen from a series of said units.

Another object is the production of a coin control by which a penny article or package can be dispensed by the use of a one cent coin or by which a series of penny articles or packages can be dispensed by the use of a coin of higher denomination such as a five or ten cent coin.

Another object is the production of a coin control by which various combinations in the mechanism can be easily effected whereby coins of various denominations can be employed to permit various numbers of dispensing units being operated by a single coin. For illustration a ten cent coin can be made to control the operation of two dispensing units.

Among further advantages are maximum simplicity of construction and dependability in successful operation.

The apparatus is applicable for controlling any desired number of dispensing units, is substantially free from jamming and is incorporated into a unit structure which can be easily detached from the dispensing control mechanism to facilitate repairing and adjusting parts without disturbing the remaining control apparatus, all of which is of particular advantage. Further objects and advantages will be apparent from the following specifications of which the accompanying drawings form part and in which Fig. 1 is a front elevation of a vending machine housing containing a plurality of dispensing units suitable to be controlled in operation by my improved control; Fig. 2 is a side elevation of my improved coin control combined with a multiple dispensing unit control, a portion of the face frame of the housing and two of the dispensing units being shown; Fig. 3 is a side elevation looking at the opposite side of the apparatus as shown in Fig. 2; Fig. 4 is a front elevation of the apparatus shown in Fig. 2; Fig. 5 is a back elevation of the apparatus shown in Fig. 2; Fig. 6 is a side elevation on a

somewhat enlarged scale of the coin control unit when omitting all but a detail portion of the dispensing unit frame and the lock base; Fig. 7 is a back elevation of the structure illustrated in Fig. 6, and showing the coin chutes in a position when the return actuator 14 is operated for the return of a coin to the operator; Fig. 8 is a section on an enlarged scale, taken approximately on the line 8—8 of Figs. 3 and 5, showing the lock base; Fig. 9 is a front elevation of a portion of the apparatus shown in Fig. 8; Fig. 10 is a section taken approximately on line 10—10 of Fig. 8; Fig. 11 is a section of a detail taken approximately on line 11—11 of Fig. 10; Fig. 12 is a section of a detail taken on line 10—10 of Fig. 8, showing the controlling catch 54 in lowered position; Fig. 13 is a diagrammatic view illustrating the action of the catch element; Fig. 14 is a side elevation of part of the coin control, when the parts shown are in normal position and illustrating only the penny chute for greater clearness and a penny in position therein when about to be released through the action of the operating catch after one of the dispensing elements 13 is pulled out when operated, a portion of the coin disk 70 being broken away to more clearly show parts of the device; Fig. 15 is a side elevation somewhat similar to Fig. 14, showing only the five cent coin chute and a coin in position immediately following the operation of a dispensing unit actuating element 13, the operating latch A and its immediately connected parts being removed and the lock pawl B swung from locking position to permit the lowering of the catch element; Fig. 16 is a side elevation of a more complete assemblage of the parts shown in Figs. 14 and 15, when the latch A and its connected parts, including the coin disk 70 are removed so as to disclose fully the complete assemblage of the coin chutes and the cooperating coin escapement rocker arm 75 and segments, all of the parts being shown when in normal position before a coin is dropped into the machine; Fig. 17 is a side elevation of the coin control unit frame at reduced scale; Fig. 18 is a front elevational view of the structure shown in Fig. 17; Fig. 19 is a side elevation of the one cent coin operating arm 109 removed from the coin control unit; Fig. 20 is a plan looking at one edge of the operating arm shown in Fig. 19; Fig. 21 is a side elevation of the frame of the five cent coin escapement rocker arm 75, separate from the coin control unit; Fig. 22 is an edge elevational view of the rocker arm shown in Fig. 21; Fig. 23 is a side elevation of a detail portion of the five cent coin disk 70 removed from the coin control, and Fig.

24 is a section of a detail taken on the line 24—24 of Fig. 23.

In Fig. 1 a type of vending machine is shown having a housing or cabinet C containing a single vertical series of dispensing units D in its face panel frame 10, of similar or different types, such as are adapted to be operated through the use of my improved coin control contained therein, suitable coin receiving slots 11 and 12 being provided through which coins of selected denomination such as pennies and nickels may be deposited for controlling the operation of the dispensing units. Suitable hand operable pull rods such as 13 are provided in the face panel for the operation of any selected dispensing unit. A coin return push plunger 14 accompanied by a coin return receptacle 15 are also provided in the face panel 10.

The present invention contemplates the selective operation of any one of a series of the dispensing units by my improved coin control unit E. As my improved coin control is particularly although not exclusively adapted for use with a particular operating mechanism a description of the same follows.

In my companion applications above referred to, I have shown and described a dispensing unit actuator such as F for operating each dispensing unit of a series, the particular coin control and interposed catch cooperating means herein set forth not being disclosed. The actuator referred to consists of suitable body members 16 assembled on the back of the face panel of the machine, one body frame for each dispensing unit being provided. Reciprocable in and out of the face panel are the suitable manually operative actuating pull rods 13, one accompanying each body member and each pull rod supporting a collet block 17. On the lower side of this block is a boss 18 and on the upper side a longitudinal series of ratchet teeth 19. The body member has a depending inner arm 20 to the lower extremity of which is pivoted at 21 an actuating lever 22, the free end of which is pivotally hung from the boss 18 by a link 23 so that as the pull rod is reciprocated longitudinally the actuating lever is swung up and down. An expansion spring 24 is loosely threaded over the shank of the pull rod between the outer portion of the body member and the block 17. This spring permits the pull rod to reciprocate outwardly and swing the actuating lever downwardly and serves to return the pull rod inwardly into normal position and swing the actuating lever 22 back into raised position. The actuating lever is provided with a pair of shoulders 25 on its side, spaced vertically apart sufficiently to admit and engage an antifriction propelling roller such as 26, indicated in Fig. 3, on the drive member, such as is illustrated in my companion applications, to propel the dispensing units by the application of reciprocable motion. It will be understood that in mounting the parts of the dispensing apparatus on the cabinet the actuator lever 22 is positioned so that the shoulders 25 cooperate with the actuating roller 26, and cause the functioning of the dispensing unit. The actuating lever 22 is shown (see Fig. 3) connected by a link 27 and clamp block 28 to one of the vertical reciprocable control rods 29, which constitute part of and cooperate indirectly through interposed selective locking means with the coin control hereinafter described, to govern the operation of any one of the dispensing units chosen by the operator. A control rod 29 is provided for each dispensing unit, the several rods

29 being grouped and reciprocable by their upper ends in suitable bearing supports 30 (see Fig. 5), on the panel frame and by their lower ends in the horizontal arms 31 of the lock base 35 as will be hereinafter described.

To cause a complete forward and return stroke being made during each operation of the machine, a double acting spring pressed pawl 32 (see Fig. 3) is freely pivoted at 33 on the body member 16 of the actuator so as to contact the ratchet teeth 19 on the sliding block 17 as the pull rod is reciprocated in either direction. This pawl 32 is retained in normal position out of contact with the teeth 19 when the pull rod is at either end of its outer or inner half stroke by a vertically hung retractile spring 34. As the pull rod is drawn out the pawl sweeps over the teeth and functions as a stop to prevent any return movement until a complete forward half stroke has been made and vice versa, after complete withdrawal and the pull rod retracts back into the machine, the pawl again sweeps over the teeth and prevents any reversal until the stroke has been completed. In this manner, jamming by improper operation and milking of the machine by thieves is prevented.

My improved coin control E is adapted to control an operating latch A, and a lock stop pawl B, through the functioning of a multiple control lock G, for normally blocking the operation of all but one of the dispensing unit control rods 29 at a time. The control lock comprises a lock base 35 resembling a yoke frame having a pair of horizontal arms 31 through which the lower ends of the members of a group of the dispensing unit control rods 29 reciprocate. As illustrated only one of the arms of the lock base is shown equipped with a cluster of control rods 29, Fig. 10, indicating by broken lines the companion arm also equipped. When desired the vacant arm of the lock base may be equipped with a set of control rods and the capacity of the apparatus which is controlled by a single coin control unit thus increased. Each of said arms of the lock base has a longitudinal cylindrical socket 36 (see Figs. 8 to 13) containing a series of tumbler lock balls 37, of corresponding size, the lower end of each rod normally registering with a tumbler ball of the series in the socket. Vertical guide openings 39 in each arm 31 provide suitable bearings for normally holding the lower ends of the control rods evenly spaced horizontally apart above one side of each ball. Only sufficient free space longitudinally in the sockets is provided to permit one control rod at a time descending between and below the tumbler balls as shown in Fig. 13. The remaining tumbler balls are retained in blocking position to prevent the remaining operating rods and their coupled dispensing units from being operated. In this manner, an automatic slide interlocking mechanism is provided for controlling the operation of the control rods so as to permit the operation of only one corresponding dispensing unit at a time. The two sockets and series of blocking balls in each are provided with a walking beam 40 pivoted by the bolt 41 on the lock supporting frame 42 below the yoke to permit free horizontal tilting movement (see Figs. 5 and 8). The opposite ends of the walking beam carry adjustable stops 43 entering the open ends of the sockets 36 against the series of tumbler balls therein to transmit motion from one series of the balls to the other. In this manner the two series of tumbler balls are connected together.

The adjustments shown provide for the close regulation of the free space in the sockets so that only one operating rod and its companion dispensing unit at a time can be operated. It will be noted that the lower end of each control rod 29 is tapered downwardly at 38 (see Figs. 10, 11 and 13) to provide a guide surface against the side of the corresponding ball in registration therewith in the socket below, whereby the rod 29 which is driven by a selected dispensing unit acts as a control or operating element by plunging downwardly between and separating the tumbler balls sufficiently to permit a full stroke while the remaining balls of the complete chain block the remaining control rods and their connected dispensing units from operating.

Each control rod is divided into upper and lower sections which are adjustably secured longitudinally through threaded engagement with a coupling element 44 (see Figs. 8 and 11) to provide longitudinal adjustment. Each coupling element has a laterally projecting coupling block 45, the several blocks being urged upwardly against the rigidly supported angle stop arm 46 (see Fig. 11) which is supported by one of the arms 31 of the lock base. A downwardly extending push pin 47 is secured rigidly to each coupling block 45, said pins being omitted from Fig. 11 for clearness in showing the complete set of operating rods 29. The lower end of this push pin reciprocates freely through and is adapted to project below the members 31 of the lock base yoke 35 when urged downwardly by the companion operating rod 29. Each operating rod 29 is provided with an expansible helical spring 48 between the block 45 thereon and the surface of the member 31 of the lock base 35 below to hold the operating rods 29 in normally raised position with their lower ends substantially out of contact with the tumbler elements 37 as shown in Fig. 11 and with the push pins 47 recessed upwardly into the corresponding arm of the lock base as shown in Fig. 10. The lock base 35 which is incorporated into the panel frame structure is rigidly mounted upon the upstanding posts 48 of the supporting frame 42 by the boss and screw connections 49 and is provided with a pair of upstanding stationary guide shafts 50 upon its median portion. A push pin locking member 51 is vertically reciprocated upon the guide shafts and has a horizontal push pin engaging plate or flange plate 52 which is juxtaposed below the lower ends of all of the push pins 47 and extends below and is urged upwardly against the lower portions of the members 31 of the lock base 35 by the expansible helical springs 53. The push pin locking member 51 can thus be driven down into lowermost position as shown in Fig. 12, by the downward thrust movement of any one of the push pins which is permitted by the chain of tumbler elements 37 of the gate. The push pin locking member 51 has an upwardly extending catch 54 with which the operating latch A and releasable lock pawl B of the coin control are adapted to cooperate to permit the operation of any selected dispensing unit through the operation of the coin control and the automatic release by the tumbler stops of the locking mechanism, as will be hereinafter described.

My improved coin control unit E is incorporated into a single skeleton body frame 60, having upper and lower flanges 61 and 62 respectively on its front and back edges, through which the holding screw elements 63 and 64 are secured respectively to the back of the panel frame and one of the arm members of the yoke 35 to support the coin

control unit with its latch A and escapement pawl B juxtaposed to the upwardly operating catch 54. In as much as this frame 60 is incorporated as a single element into the construction of the several elements constituting my improvement, it is shown in detail stripped from all adjunct parts for greater clearness and at reduced scale in Figs. 17 and 18. By its use the entire unit can be easily and quickly detached and removed for adjusting, repairing and replacement when desired, which is a distinct advantage. A space is provided in the upper end of the frame for the application and use of a slug eliminator. As the eliminator is conventional and well known the same for greater clearness of the control mechanism is omitted from the drawings excepting in Fig. 6 where it is indicated in outline as identified by ordinal 66. In the forward portion of the body frame 60 a coin return chute 65 (see Figs. 2 and 16), is provided which leads from the eliminator 66 to the coin receptacle 15 (see Fig. 1), in the face of the panel for the return of inoperative and objectionable coins including slugs. In Fig. 6 a conventional slug eliminator is shown above and in registration with the coin and slug chutes which are employed in my improved coin control.

The coin control E has a vertically disposed escapement disk 70, journaled concentrically on a horizontal shaft 71 which is bolted at 72 on one side of the median portion of the body frame 60 (see Fig. 17). The disk may be designed to cooperate with a five or ten cent coin as desired. The disks may be interchangeable and for convenience only the five cent type is referred to in the following description, in detail as illustrated in Figs. 23 and 24. The coin disk is provided with a circumferential series of coin holding shallow cups or sockets 73 in its periphery, the floor 73' of each cup having a circular contour to receive the periphery of and hold the coins such as 74, as indicated in Fig. 15. A retaining wall 74' (see Fig. 24) is provided on the outer side of each cup while the adjacent flat side of the coin operating rocker arm 75 assists in holding the coins in upright position in the cups for a short distance after receiving them and while the disk is revolved step by step forwardly by suitable ratchet mechanism to be hereinafter described.

The operating arm 75 shown in detail in Figs. 21 and 22, conforms with an arc about the perimeter of the coin disk and is tiltingly mounted to rock at its lower end by the stud bolt 76, on the side of the lower portion of the body frame 60, leaving its upper portion free to swing freely toward and away from the perimeter of and at the inner side of the coin disk. The outer circular margin of the rocker arm is provided with a circular series of coin escapement segments 77, suitably fastened by screws 78 (see Fig. 2), or other suitable means on the perimeter of said rocker arm. The segments in cooperation with the coin disk provide a circular coin channel or path downwardly through which the coins are adapted to pass step by step through the series of segments 77 and to be ejected downwardly and dropped into a chute 79 leading into a coin receiving container such as 79' (see Fig. 4). The outer end of each segment has a pair of antifriction roller bearings 80 journaled and secured below inner side coin guide plates 81 by screws 82 or other suitable means. The upper end of the rocker arm 75 is swung inwardly and normally held adjustably depressed against an edge of the body frame 60 below an adjustable stop 83 (see Fig. 2) by a retractile spring 84 so as to confine the width of the

channel or path between the cups in the coin disk and the bearing rollers 80, whereby a coin entering the upper end of the channel or path is permitted to escape downwardly step by step by the segments as the coin escapement rocker arm is reciprocated and while the coin disk is correspondingly stepped forwardly by its ratchet drive. The stop 83 it will be noted is mounted at one side of the rocker arm 75. A projecting portion of the lower end portion of the rocker arm carries an actuating stud 85 which slidably engages in a guide slot 86 through an offset portion of the lock pawl B. Said lock pawl is freely hung by a pivot support 87 on one side of the lower portion of the body frame 60. The lower end of the pawl has a shoulder 88 which is held, in the normal position of the rocker arm 75, below and in the path of the catch 54 on the key element 51 to block the operation of the ratchet mechanism and any of the dispensing units until the rocker element is tilted outwardly under the influence of a coin and through the consequent action of the actuating stud 85 sliding in the guide slot 86.

Placed above the uppermost end of the rocker arm 75 are two coin chutes 90 and 91, leading from suitable positions for the admission of coins as passed by the slug eliminator downwardly. The chute 90 has a passageway of suitable size to transmit five cent coins while chute 91 has a passageway of suitable size to transmit only one cent coins. These chutes are rigidly secured together at their upper ends and are freely hung from a supporting shaft 93 so as to swing laterally. The lower ends of the chutes converge and are secured together such as by screws 94 or other suitable means, with the channel orifice of the five cent chute normally in juxtaposition with the escapement channel or path above described and with the channel orifice of the one cent chute normally in juxtaposition with a free passageway provided along side of the segments 77 and above the delivery chute 95 leading to the coin container 96 (see Fig. 3). The lower ends of the coin chutes 90 and 91 are shiftably sustained on shaft 93 in normal position by an expansion spring 97 (see Fig. 7) which normally urges the chutes outwardly against an adjustable stop 98, a suitable integral retaining web 99 (see Fig. 6) being provided on a portion of chute 90 through which the stop functions.

The lower ends of the pair of coin chutes 90 and 91 are cut away to provide a downwardly projecting coin guide 100 through which the coin passages in the chutes extend. The upper portion of the escapement rocker arm 75 immediately above the series of segments 77 has a terminal stop segment 101, the inner side surface of which lies in the plane of the inner surfaces of the chain of escapement segments 77. The outer end surface of the stop segment conforms with the outer concave lower end of the coin guide on the coin chutes 90 and 91 and normally is held by the rocker arm 75 adjacent thereto. This stop segment carries a guide plate 102 (see Fig. 7) corresponding with and in extension of the series of plates 81, with a spacer 103 and antifriction roll 104 therebetween, forming guide surfaces for the five cent coin delivered by chute 90 to the series of rollers held by segments 77. An antifriction guide roller 105 is also mounted by bolt 105' on the face of the stop segment 101, in position to normally sustain the one cent coin in chute 91 and guide the same downwardly from the lower end of said chute when released. The upper inner portion of the rocker arm 75 is provided with an ad-

justable coin stop 106, which assists in guiding the five cent coin as it slides down from the five cent coin chute into the corresponding cup in the coin disk and functions to prevent coins from entering the escapement passageway provided by the rocker arm 75 and coin disk 70 as the coin disk is stepped forwardly by the operation of a dispensing unit. During each successive rotation step forwardly of the coin disk, the five cent coin progresses downwardly from segment to segment in the coin path, there being five segments and five steps forwardly, representing the operation five times of any of the associated dispensing units and the delivery of a penny article or package each time. During each operation the rocker arm is tilted radially outwardly by the five cent coin in the escapement passage sufficiently to swing the lock pawl B from catch engaging position shown in Fig. 14 into releasing position shown by the full lines in Fig. 15. The spacing of the coin cups in the coin disk and the spacing of the escapement segments and rollers substantially corresponds so that the coin is firmly held in the cup and below each corresponding pair of antifriction rollers in the corresponding segments. When the five cent coin reaches and is discharged from the lowermost segment it drops into the chute 79 which in turn guides it downwardly and deposits it into the receptacle such as 79'.

Normally the lock pawl B prevents the operation of the reciprocable push pin locking element 52 and its catch 54 sufficiently to permit the latch A functioning. This latch when engaged and operated by the element 54 of the push pin locking element 52 actuates the ratchet mechanism which in turn rotates the coin disk a step forwardly. A ratchet wheel 89 is rigidly mounted upon the shaft 71 which carries the coin disk 70 on the body frame and has a series of ratchet teeth in its periphery with which the ratchet dog 108 engages intermittently. The body of this dog is pivoted upon one end of the one cent coin operating arm 109. The median portion of this arm is tiltingly mounted upon the shaft 71 which carries the coin disk and ratchet wheel and the opposite end of the arm is provided with an upwardly extending shoe 110 which is reciprocated in an arc each time the operating arm 109 is reciprocated. A retractile spring 111 between the free end of the dog 108 and the operating arm 109 tends to hold the dog engaged with the ratchet teeth. The end of the operating arm 109 which carries the shoe is operatively connected with the latch A by the link 112. This link carries a ratchet lock release arm 113 which releasably engages a pin 114 on the side of a ratchet lock arm 115, to withdraw by swinging movement a pin 116 from locking engagement with the teeth of the ratchet wheel 89. A retractile spring 117 connected with one end of the lock arm 115 and a rigid portion of the frame structure serves to automatically tilt the arm 115 on its pivot support 115' and cause its pin 116 to engage the teeth of the ratchet wheel and normally lock the latter from revolving. The connections 113 at the upper and lower ends of the link 112 are loose and the lower end has a leaf spring 119 on its side below the lower connecting screw element 118. The loose connections 118 at the upper and lower ends of link 112, permit the lower end of link 112 to tilt outwardly so as to permit disengagement of the ratchet lock release arm 113 from pin 114 on said arm. The leaf spring 119 tends to hold the member 113 in engagement with said pin but permits member 113 to slide over the end of and reengage the pin as the ratchet

lock arm swings on its pivot support and returns to normal position. The tilting of link 112 outwardly to disengage the ratchet lock release arm 113 from pin 114 is caused by a beveled shoulder 114' on the side of member 115 as member 115 is swung down by member 113 with its pin 116 out of engagement with the teeth of the ratchet wheel 89. The ratchet mechanism thus provided cooperates with the lock catch A, whereby as the link 112 is drawn down by the catch it trips the arm 113, by tilting, to disengage the pin 114 automatically immediately following the disengagement of the pin 116 from the teeth of the ratchet wheel so that the pin 116 will engage the next succeeding tooth of the ratchet wheel as the latter is revolved and only permits step by step revolution of the coin disk a distance corresponding with one coin release segment at a time. The pin 116 remains engaged to lock the ratchet wheel 89 and prevent the further rotation thereof by the operation of a coin until the lock release arm 113 is reset by sliding over the outer beveled end of pin 114, whereupon the arm 113 and link 112 are tilted outwardly and the arm 113 reengages in readiness for a succeeding operation of the lock catch A. It will be noted that the outer end of pin 114 is beveled outwardly towards the observer of Fig. 14 and upwardly to provide a guiding surface for tripping the arm 113 into reengagement with the pin 114 under the backward tilting movement of link 112 and arm 113, which is caused by the leaf spring 118, when the operating latch A is released and permitted to swing up. In this manner when a five cent coin is used and one cent articles or packages are dispensed, five operations of one or different dispensing units are permitted automatically by my improved coin control.

The one cent coin control which is operated each time a one cent coin enters chute 91, in conjunction with part of the five cent coin control apparatus above described by the operating pull element 13 of any of the dispensing units, consists in part as follows: The shoe 110 has a shallow coin receiving socket 120 which normally registers with the lower end of the coin guide 100 immediately below the coin passage in the one cent coin chute 91 so that each one cent coin, such as 121, when dropped through chute 91 will be retained by the shoe while lodged against the antifriction guide roller 105. When subsequently a dispensing unit is operated the coin is passed forwardly by the shoe thus pressing against the guide roller 105 and swinging the escapement rocker arm 75 outwardly sufficiently to swing the lock pawl B away from a position blocking the downward thrust of the operating catch 54. Continued forward movement of the one cent coin operating arm 109 and its shoe discharges the coin held by the latter, into the delivery chute 95 which is held on the escapement rocker arm 75. The delivery chute serves to deposit the coin in a suitable container such as 96 as shown in Fig. 3. The throw of the coin operating arm 109 forwardly caused by the operation of the dispensing unit to release an article or package is produced by the ratchet mechanism above described and in the same manner and through substantially the same distance as when the apparatus is operated by the use of a five cent coin. One operation of the operating arm 109 when a one cent coin is deposited in the machine thus serves to release the coin, whereas, when a five cent coin is deposited in the machine five operations are required to release the latter coin.

The shoe 110 has a follower arm 123, the upper

surface of which acts as a retainer for holding any coins in chute 91 other than the one which is being directly held and operated by the shoe. When the shoe returns to normal position any immediately subsequent coin in the chute will drop into the coin socket and into engagement with the operating arm 109 in readiness so that a dispensing unit may be operated.

The apparatus is provided with cooperating means for returning coins to the operator after dropping them into the coin receiving slots 11 and 12 and before operating the control elements 13. This coin return means is provided in part by the swinging support of the rigidly held pair of coin chutes 90 and 91, which are adapted to be swung outwardly from the position shown in Fig. 5 into the position shown by Fig. 7, with their lower ends out of registration with the coin escapement means provided by the arm 75 and the shoe 110. This swinging movement is produced by pressing the coin return push plunger 14 inwardly, said plunger being reciprocably held on one side of chute 65 (see Figs. 2 and 6) under the return action of an expansion helical spring 125 in a suitable housing 126. The inner beveled end 127 of the plunger is adapted to press against a beveled guide bearing 128 on the side of the chute retaining web 99 so that when the plunger 14 is pressed inwardly the coin chutes 90 and 91 are swung outwardly from normal position and when the plunger is released the expansion spring 97 (see Fig. 7) returns said chutes to normal position automatically. When in outwardly swung position the lower open ends through the coin guide 100 of the pair of chutes 90 and 91 register with a downwardly slanting return chute 129 traversing the body frame 60 and connected with the coin return receptacle 15 in the face panel frame 10 of the dispensing machine.

In this manner the operator has full control of the dispensing units and can at will after dropping a coin into the apparatus cause the return of the coin before operating any of the dispensing units. The lower end of the return chute 129 merges into the slug eliminator chute 65 so that an orifice leading from both enters the single coin return receptacle 15.

Operation

When it is desired to operate the apparatus, assuming that one cent coin is placed in the penny slot 11, the coin after passing the eliminator continues down the chute 91 into the socket 120 of the shoe 110. The hand operable actuating element 13 of the dispensing unit it is desired to operate is then operated by pulling it outwardly, thus causing the corresponding control rod 29 to function and plunge the companion push pin 47, push pin locking plate 52, carrier 51, and operating catch 54 downwardly from normal position. During the first portion of the movement of the catch downwardly the operating latch A is engaged and swung downwardly by the operating catch 54, thus swinging the coin operating arm 109 sufficiently to propel the coin and the arm 75 outwardly together with the lock pawl B, out of blocking position. The continued movement of the catch downwardly causes arm 109 and its shoe to tilt forwardly and discharge the coin into the chute 95 and thence into the receptacle 96. During this action the ratchet mechanism functions automatically to permit the operation of the arm 109. This movement occupies the entire outward portion of the stroke of the hand operable pull element 13.

Release of said pull element permits the parts to return to normal position automatically. It will be noted that an interval occurs when the operating catch starts moving downwardly until blocked by the lock pawl, during which the arm 109 cannot actuate the ratchet wheel 89 unless a coin is interposed in the socket 120 and the free end of the rocker arm 75 and thereby release the element 54 from the element B. Should another one cent coin be placed in the one cent chute 91 before or during the propulsion of the preceding coin by the shoe 110, the follower 123 on the shoe holds the succeeding coin or coins in the chute until the coin operating arm 109 returns to normal position. However when the coin is in place the ratchet mechanism is released to permit the propulsion of the coin and consequent swinging of the arm 75 outwardly sufficiently to move the lock pawl B out of blocking position and permit the discharge of the coin.

When a five cent coin is placed in the nickel slot 12, and after passing the eliminator 66, slides down the five cent coin chute 90, it lodges in the corresponding cup of the coin disk and against the uppermost antifriction roller 104, in position to push the escapement arm 75 outwardly on its rocker support 76 as the coin disk is subsequently revolved forwardly in the direction of the arrows shown in Fig. 6. The actuating elements 13 of the dispensing units it is desired to operate are then successively operated until five have functioned to dispense one cent articles or packages. Each successive operation causes the coin disk to revolve a step forwardly through the coin path below the five escapement segments until finally after five operations the coin is discharged into the coin chute 79 and thence into the coin receptacle 79'. During each operation the lock pawl B is first swung from normal blocking position shown in Fig. 14 into releasing full line position shown in Fig. 15 and the operating latch A is engaged by catch 54 to cause the operation of the ratchet mechanism and the step by step revolution of ratchet wheel 89 and the coin disk 70. At the end of each complete reciprocal movement of the coin propelled rocker arm 75, the lock pawl B functions to block the movement of the operating catch 54. Should another five cent coin be placed in the five cent chute 90 during the passage of a coin through the escapement mechanism by the coin disk 70 and escapement rocker element 75, the stop 106 intercepts the delivery of the coin into the escapement mechanism until the coin previously admitted has been discharged into the chute 79 and container 79'.

If it is desired by the operator to return a coin previously deposited in the chutes 90 and 91, before operating the dispensing units, the plunger 14 (see Fig. 6) can be operated to swing the chutes into registration with the return chute 129 as shown by the full line position in Fig. 7, whereupon the coins will pass downwardly through chute 129 into the return receptacle 15.

It will be noted that in normal position the chutes 90 and 91 are juxtaposed over the channel through the segments of the coin escapement and over the channel between the stop segment 101 and the shoe 110 as shown in Fig. 5.

Should it be desired to repair or adjust the parts, or to replace the unit in its entirety the same can be detached by removing the fasteners 63 and 64 (see Fig. 7), whereupon the entire coin control unit can be easily and quickly re-

moved from the multiple dispensing unit operating mechanism.

The above apparatus is susceptible by slight modification of being operated by a coin of five, ten or larger denomination, to dispense articles through a selected number of operations of the dispensing units, in which event the coin disk and ratchet mechanism are proportioned and caused to coact and the segments are altered in number accordingly. To illustrate, the parts may be made to dispense two articles by a single coin in which event only two segments are employed. After operating a dispensing unit twice or after two operations of different units the coin of required denomination is expelled into the retainer 79.

The term "coin" as used throughout this specification and the claims following is intended to include true coins of the realm and coins frequently referred to as checks or tokens.

In accordance with the patent statutes, I have described the principles of operation of my invention, together with the apparatus which I now consider to represent the best embodiment thereof, but I desire to have it understood that the construction shown is only illustrative and that the invention can be carried out by other means and applied to uses other than those above set forth within the scope of the following claims.

I claim:

1. In a mechanism of the class set forth, the combination of a coin pathway, means for effecting a series of step by step movements of a coin of one size and multiple denomination through said pathway, means for actuating said step by step effecting means, means for locking said step by step effecting means at the end of each step in operation to compel a series of coin actuating operations corresponding with the denomination of the coin in use and until the coin in use is released at the end of each series of operations, and a rocker member associated with said pathway and actuated successively by the coin in use as it is subjected to said step by step movement for releasing and restoring the locking means to operative condition successively and at the conclusion of a predetermined number of operations of said step by step movement effecting means.

2. In a mechanism of the class set forth, the combination of a coin pathway, a coin chute in registration with said pathway for delivering a coin thereto, means for effecting a series of step by step movements of a coin of one size and multiple denomination through said pathway, means for actuating said step by step effecting means, means for locking said step by step effecting means to compel a successive step by step forward operation corresponding with the denomination of the coin in use and until the coin in use is released at the end of each series of steps, and reciprocal means associated with said pathway and controlled by the coin in use as it is subjected to said step by step movement for releasing and restoring the locking means to operative condition successively and at the conclusion of a predetermined number of actuations of said step by step movement effecting means.

3. In a mechanism of the class set forth, the combination of a rotary coin engaging disk having a series of coin holders in its periphery, a coin chute in registration with and adapted to introduce a coin of multiple denomination into one of said coin holders to be propelled step by step through a coin pathway by said disk, means for effecting a series of rotary step by step opera-

tions forwardly by said disk corresponding in number with the denomination of the coin in use, means for locking the disk against movement at the end of each step in operation, and a reciprocable coin controlled operating member coinciding substantially with the periphery of said disk and movable to releasably hold a coin engaged thereby, said coin controlled operating member being connected with said locking means to actuate the latter by a coin and release the locking means during each step forwardly, and said coin controlled operating means functioning to release a coin from engagement with the disk at the end of the series of steps in operation of the disk.

4. In a mechanism of the class set forth, the combination of a rotary coin propelling disk having a series of coin holding cups in its periphery, means for introducing a coin into one of said cups to be propelled by the disk, means for rotating said disk step by step forwardly to advance said coin by said movements, a coin propelled rocker member swung about the periphery of said disk to hold the coin engaged by said disk as the latter is rotated step by step forwardly, said rocker member having a rack coinciding with said cups and engaged by a coin held by the disk to reciprocate the rocker member outwardly each step forwardly of the disk, and means normally locking the disk against movement, said locking means being connected with said rocker member to be operated by each movement thereof and serving to release the coin from engagement therewith at the end of a predetermined series of movements.

5. In a machine of the class set forth, the combination of a rotary coin propelling element having a train of coin holders movable thereby, means for introducing a coin of multiple denomination into one of said holders at substantially the head end of said train, means for driving said propelling element forwardly by a series of movements corresponding in number with that of a denomination of said coin, a reciprocably supported operating member having a rack cooperating with said propelling element and depressible by the coin during each movement of said propelling element, said propelling and operating elements releasing the coin at the delivery end of said series of movements, and locking means cooperating with said driving means and controlled by each reciprocable movement of said operating member.

6. In a combination of elements as defined in claim 5, the rack being composed of a supporting structure and a series of spaced antifriction rollers between which the coin is adapted to be successively engaged by the movements of the propelling element to reciprocably operate the locking means.

7. In a mechanism of the class set forth, the combination of a rotary coin propelling disk having a series of coin holding cups on its periphery, a coin chute for introducing a coin into one of said cups to be propelled by the disk, means for driving said disk step by step forwardly to advance said coin a predetermined series of steps, a coin propelled reciprocable member cooperating with the periphery of said disk to hold the coin engaged by said disk as the latter is rotated step by step forwardly, said reciprocable member having a rack coinciding with said cups and engaged by a coin held by the disk to operate the reciprocable member outwardly during each forward movement of the coin by the disk, means

normally locking the disk against movement, said locking means being connected with said reciprocable member to be operated by each outward movement thereof and serving to release the coin from engagement with said disk at the end of a predetermined series of movements, and means cooperating with said disk driving means for preventing more than one coin entering the disk at a time and until a series of movements have been completed.

8. In a mechanism of the class set forth, the combination of a rotary coin propelling element having an annular series of coin holding cups, a coin chute for introducing coins into said cups, means for actuating said rotative element to advance a coin held in said cups step by step, a lock controlling the operation of said rotative element, a coin propelled reciprocable member cooperating with a coin held in one of said cups to be reciprocated thereby through the step by step rotative movement of said propelling member, and a stop carried by said reciprocable member normally intercepting the delivery of coins from said chute until a coin previously admitted into said cups has been discharged.

9. In a mechanism of the class set forth, the combination of a rotary coin propelling element having an annular series of coin holding cups, a support upon which said propelling element is journaled, a coin chute hung from said support and normally registering with said cups to discharge coins thereinto, means for swinging said chute out of registration with said cups to divert and return coins to the operator, means for rotating said propelling element step by step to advance a coin a series of operations corresponding with its denomination, a lock for normally blocking the operation of said propelling element, and a reciprocable element on said support connected with said lock to release the latter, said reciprocable element cooperating with said cups and having a rack juxtaposed over said cups to be reciprocated by a coin held in said cups as the latter are propelled forwardly by the step by step rotary movement of said coin propelling element.

10. In a mechanism of the class set forth, the combination of a coin pathway, means for effecting a series of step by step movements of a coin of one size and multiple denomination through said pathway, means for actuating said step by step effecting means, means for locking said step by step effecting means at the end of each step in operation to compel a series of coin actuating operations corresponding with the denomination of the coin in use and until the coin in use is released at the end of each series of operations, reciprocable means associated with said pathway and controlled by the coin in use as it is subjected to said step by step movement for releasing and restoring the locking means to operative condition successively and at the conclusion of a predetermined number of actuations of said step by step movement effecting means, a chute for a coin of different size and of single denomination having its discharge and juxtaposed to said reciprocable means and releasably blocked whereby to normally retain a coin in said chute, and operating means impelled by said step by step actuating means and engaging the coin in said chute to discharge the same and simultaneously actuate the reciprocable means and release the locking means, whereby the step by step effecting means is permitted to function.

11. In a mechanism of the class set forth, the

combination of a rotary coin propelling element having an annular series of coin holding cups, a support upon which said propelling element is journaled, means for driving said propelling element step by step to advance a coin of multiple denomination a series of operations, locking means for normally blocking the operation of said propelling element, a rocker element mounted upon said support having a reciprocable actuating connection with said locking means and a rack juxtaposed to said cups to reciprocate the rocker element and release said locking means by a coin held in one of said cups each time the propelling element is operated, a coin chute normally coordinating with one of the cups in the coin propelling element to deliver a coin of multiple denomination thereto, a second coin chute adapted to deliver a coin of single denomination, said rocker element having a guide normally sustaining the coin of single denomination in its chute and movable when reciprocated to release the coin, and an operating member actuated by said driving means for engaging the coin of single denomination at the delivery portion of its chute and reciprocating the rocker element to release said coin from its chute and effect the release of the locking means.

12. In a mechanism of the class set forth, the combination of a rotary coin propelling element having an annular series of coin holding cups, a support upon which said propelling element is journaled, means for driving said propelling element step by step to advance a coin of multiple denomination a series of operations, locking means for normally blocking the operation of said propelling element, a rocker element mounted upon said support having a reciprocable actuating connection with said locking means and a rack juxtaposed to said cups to reciprocate the rocker element and release said locking means by a coin held in one of said cups each time the propelling element is operated, a pair of coin chutes shiftable upon said support, one normally coordinating with one of the cups in the coin propelling element to deliver a coin of multiple denomination thereto and the second adapted to discharge a coin of single denomination, said

5 rocker element having a guide normally sustaining the coin of single denomination in its chute and reciprocable to release the coin, an operating member actuated by said driving means for engaging the coin of single denomination at the delivery portion of its chute and reciprocating the rocker element to release said coin from its chute and effect the release of the locking means, a return coin chute from the discharge of said 10 pair of chutes, and means for shifting said pair of chutes into registration with said return chute to effect the return of coins therefrom to the operator.

13. In a mechanism of the class set forth, the combination of a rotary coin propelling element having an annular series of coin holding cups, a support upon which said propelling element is journaled, means for driving said propelling element step by step to advance a coin of multiple 15 denomination a series of operations, locking means for normally blocking the operation of said propelling element, a rocker element mounted upon said support having a reciprocable actuating connection with said locking means and a rack juxtaposed to said cups to reciprocate the rocker element and release said locking means by a coin held in one of said cups each time the propelling element is operated, a coin chute normally 20 coordinating with one of the cups in the coin propelling element to deliver a coin of multiple denomination thereto, a second coin chute adapted to deliver a coin of single denomination, said rocker element having a guide normally sustaining the coin of single denomination in its chute and movable when reciprocated to release the coin, and an operating member actuated by 25 said driving means for engaging the coin of single denomination at the delivery portion of its chute and reciprocating the rocker element to release said coin from its chute and effect the release of the locking means, said operating member having retaining means for holding subsequent coins of single denomination in their chute other than the one which is being discharged by said operating member.

CHARLES F. PEASE.
